UNITED STATES PATENT OFFICE.

CHARLES W. BALLMAN, OF INDIANAPOLIS, INDIANA.

SCAFFOLD BRACKET.

Application filed August 6, 1923. Serial No. 656,010.

To all whom it may concern:

Be it known that I, CHARLES W. BALLMAN, a citizen of the United States, and a resident of Indianapolis, county of Marion, and State of Indiana, have invented a certain new and useful Scaffold Bracket; and I do hereby declare that the following is a full, clear, and exact description thereof, reference being had to the accompanying drawings, in which like numerals refer to like parts.

This invention relates to adjustable scaffold brackets and in the present invention the same are reversible, as shown in the prior Patent No. 328,999 dated October 27, 1885.

This invention is an improvement upon the same and the chief object of the invention is to construct the reversible scaffold bracket so that it may be collapsed into compact form to facilitate the transportation thereof.

Another object of the invention is to construct the bracket hook in such a manner that the same is not only reversible as shown in the prior patent, but also is substantially unitary, thereby preventing the loss of certain securing parts heretofore employed.

The chief features of the invention consists in the unitary construction, as before indicated, of the bracket whereby the objects mentioned are accomplished.

The full nature of this invention will be understood from the accompanying drawings and the following description and claims.

In the drawings Fig. 1 is a side elevational view of a wall, a pair of ladders, a pair of platforms associated with each of which is a pair of scaffold brackets, one of the platforms being shown in the suspended position and the other being shown in the upholding position. Fig. 2 is an enlarged sectional view of the invention and is taken on the line 2—2 of Fig. 1 and in the direction of the arrows. Fig. 3 is a perspective view of the scaffold bracket showing the same in the collapsed position. Fig. 4 is an enlarged side elevation of the bracket hook positioned upon a supporting bar. Fig. 5 is an end view of the same with parts broken away to show said parts in section and to show other parts in detail. Fig. 6 is an end view and a central section of a modified form of mounting.

In the drawings 10 indicates a wall that supports a pair of ladders having the side bars 11 and the rounds 12. To construct a scaffold a platform 13, which is herein shown

in the form of the plank, is provided and associated with the same is a pair of scaffold brackets which supports said platform upon said inclined ladders. The scaffold brackets are adapted to uphold the platform, as shown in the upper part of Fig. 1, or are adapted to suspend the platform, as shown in the lower part of said figure. In both cases the platform is supported by the inclined ladders by means of the brackets. Since a bracket of the general type disclosed herein has been previously described in the before mentioned patent, no further description of this construction is necessary, except so far as the same relates to the particular improvements in the invention.

As shown clearly in Fig. 3, the bracket hook comprises a pair of spaced round engaging portions 15 which are connected by the angular extensions 16 to the bar portions 17, and herein said bar portions lie parallel to each other and are suitably secured together by the rivets, bolts or spot welding 18. The opposite ends of the bars 17 are offset as at 19 to form a pair of parallel portions 20 which are apertured at 21 to receive a pivot pin 22. The aforesaid construction, therefore, essentially consists of two complementarily formed members which form a round engaging multiple hook and a bifurcated socket. A supporting bar 23 is provided with an angular extension 124 and said angular extension is pivotally supported by the pin 22 in the bifurcated socket 20 previously described. The other and free end of the bar 23 is suitably apertured as at 24 and these apertures provide for adjustment. The bracket hook is slidably supported upon said supporting bar 23 and the other end of said bar terminates, if desired, in an offset and retaining portion 25 to prevent the accidental removal of said bracket hook from the bar and thus prevent its loss.

The bracket hook is of the general type disclosed in the before mentioned patent and consists of oppositely directed wings 26 which have a round engaging portion 27 and these wings are secured to the socket portion 28 having a passage 29 therethrough adapted to slidably receive the bar 23. Adjacent said apertured portion and extending transversely thereof is a boss 30 which is recessed at 31 substantially transversely of the aperture 29 and said recess is further extended to form the opening 32 which slidably supports the reduced end 33 of the

plunger 34 slidably supported by the recess 31. Interposed between the plunger 31 and the head of the boss thus formed is a spring 35 which at all times tends to maintain the plunger 34 in the projected position. The means for retracting said plunger consists in Figs. 1 to 5 inclusive of a transverse pin 36 which is associated with the extended portion of the stem 33 slidably supported in the opening 32.

In Fig. 6 a modified form of this last construction is illustrated and herein the stem 133 has a threaded end 140 to receive a threaded washer 141 of a diameter slightly greater than the outer end of the boss. The head of the threaded stem is then enlarged by being peened or riveted as at 142. This provides a grasping portion which is the equivalent of the pin 36 but provides an annular grasping portion, whereas the pin provides but a two point grasping portion. As shown clearly in Fig. 5 retraction of the plunger 34, with the resultant compression of the spring 35, withdraws the plunger 34 from the opening 24 in the bar 23 and permits said bracket hook to be slid longitudinally of said bar so that the plunger thereafter may register with another one of the openings 24. When such registration is secured the plunger is released and is seatable in the selected opening 24. It will be noted, therefore, that at no time is there any complete disassociation of any of the parts previously described and, therefore, there is no dropping of the securing pin bolts and the like which heretofore has been the practice.

When two workmen heretofore were constructing the scaffold, they each supported the platform in the desired position and thereafter placed the usual scaffold bracket in position upon the ladder and moved the bracket hook to the hook position where the platform was level. In such movement, frequently, the securing means for the hook was dropped by the workmen, and this necessitated both workmen returning to the ground with the platform while the first workman recovered the securing means, if the same could be found.

With the present invention, therefore, at no time is there complete disassociation of any one of the parts and furthermore the parts are so constructed that they are rela-

tively collapsible into a compact form heretofore not disclosed.

55

The invention claimed is:

1. A unitary collapsible and adjustable scaffold bracket comprising a bar having an end extending angularly thereof, bar means pivotally associated at one end with said angular end and having rung engageable portions at the other end, a stop upon the other end of the bar, said bar having a plurality of recesses in longitudinal arrangement adjacent said stop, a rung engageable reversible hook having oppositely positioned rung engaging portions and slidably supported upon said bar and a locking plunger permanently carried by said hook and receivable by any one of said recesses for locking said hook in the desired position, said hook being permanently secured to said bar by said stop, said bar means and hook being movable into collapsed position and said angular portion of said bar being adapted to limit outward movement of a supporting member supported by said bar means.

60

2. In a hook of the character described the combination of a main body portion adapted for the slidable reception of a transversely recessed bar, a lateral projection on said body including an aperture extending through said projection and including a reduced portion adjacent the outer end thereof, a locking plunger slidable into said transverse aperture and projecting therefrom into and normally positioned within the main body, a stem extending through said reduced portion of the aperture and secured at one end to the plunger and projecting outwardly from the projection for withdrawing the plunger from the body into the projection aperture, a manually engageable portion permanently secured on the exposed portion of said stem for limiting sliding movement of the stem and the plunger in the locking direction, and a spring seated within the projection and concentric with the stem and bearing at opposite ends upon the plunger and the wall of the reduced portion of the projection aperture for normally maintaining said plunger within the body and in locking position.

65

In witness whereof, I have hereunto affixed my signature.

CHARLES W. BALLMAN.
